MEANS FOR ATTACHING BOTTOMS, PANS,
AND THE LIKE TO CAGE STRUCTURES

Earl W. Little, Indianapolis, Ind.

Application March 2, 1931. Serial No. 519,451

2 Claims. (Cl. 119—17)

This invention relates to means for attaching bottoms, pans and the like to cage structures and is designed primarily for use in connection with bird cages and one feature of the invention is the provision of means for hingedly attaching the bottom forming portion of the cage structure to the body portion thereof.

A further feature of the invention is the provision of means for retaining the bottom forming portion in closed position.

A further feature of the invention is the provision of means for retaining a pan structure within the lower portion of the cage structure.

A further feature of the invention is the provision of means for concealing from view the means for retaining the bottom forming element in closed position.

Other objects and advantages will be herein-after more fully set forth and pointed out in the accompanying specification.

In the accompanying drawing which is made a part of this application,

Figure 1 is an elevation of the lower portion of a cage structure.

Figure 2 is an enlarged diagrammatic transverse sectional representation thereof, constructed upon a plane indicated by line 2—2 of Fig. 1, indicating the bottom forming portion in open position by dotted lines and showing the cage structure only where it intersects the plane.

Figure 3 is an enlarged detail sectional view of the hinge portion of the device, and,

Figure 4 is a horizontal sectional view as seen along line 4—4, Fig. 3.

Referring to the drawing the numeral 1 indicates the lower portion of a cage structure, within the lower end of which is placed a band 2, having at its top edge an inwardly projecting ledge 3, said band 2 being substantially inverted L-shaped in cross section.

Cooperating with the lower end of the cage structure 1 is a bottom forming member 4, which may be of any preferred design and configuration, said bottom forming member having a peripheral flange 5, of a diameter to enter the band 2, when the bottom forming member 4 is in closed position.

In order to hingedly attach the bottom forming member 4 to the cage structure 1, a bracket 6 is connected in any suitable manner to the inner face of the band 2 and beneath the ledge 3, said bracket having a tongue 7, which is adapted to be bent substantially J-shaped with the free end thereof projecting upwardly through a slot 8 in the flange 5 for hinging the bottom

forming member 4 to the bracket 6. In order to prevent the bottom forming member 4 from casually releasing from the tongue 7, the ends 9 of the bracket 6 are bent inwardly at right angles to the face of the bracket and over the flange 5, said ends 9 being substantially tri-angular shaped to provide inclined edges 10.

In order to hold the bottom forming member 4 in closed position, a latch 11 is placed at the edge of the cage forming structure 1 opposite the bracket 6, said latch being carried by an ornamental post 12, the upper portion of which is attached in any suitable manner to the cage structure 1 and at a point adjacent to the upper end of the post 12, as by means of a pin or rivet 13, thus leaving the lower end of the post in position to be swung outwardly for releasing the latch 11 from the flange 5 of the bottom forming member 4. The post 12 is normally held inwardly so as to maintain the latch 11 in position beneath the flange 5, for holding the bottom forming section in closed position, by means of a spring 14, said spring being spiraled around a stem 15, carried by the post 12, said stem 15 projecting through the wall of the cage structure 1 and having a head 16 at its inner end which confines the spring on the stem and causes said spring to compress when the lower end of the post 12 is swung outwardly to remove the latch 11 from the path of the flange 5, when the bottom forming section 4 is to be swung to open position.

Cooperating with the bottom forming member 4 is a pan structure 17, a portion of which preferably rests on the flange 5, while the upper peripheral edge of the pan structure is provided with a lateral extension 18, which normally fits beneath the ledge 3 of the band 2.

The distance between the flange 5 and lateral extension 18 is such that by releasing the outward pull on the lower end of the post 12, as soon as the flange 5 has released therefrom, the latch 11 will pass beneath the extension 18 and retain the pan within the confines of the cage structure until the latch is again moved out of the path thereof. In entering the pan structure 17 into the cage structure or body 1, one edge of the extension 18 is first rested against the inclined edges 10 of the bracket 6 and edgewise pressure applied to the pan, which will cause the pan to slide upwardly on the inclined edges of the ends 9 and assume a position below the ledge 3 and by forcing the opposite edge of the pan structure past the latch 11, the pan structure will be held in fixed position within the cage 110

structure until such time as the bottom forming portion 4 may be swung to closed position and engaged with the latch 11.

In removing the pan structure from the cage 5 for cleansing or other purposes, the lower end of the post 12 is moved outwardly until the latch 11 is clear of the flange 5 and extension 18, when the bottom forming portion 4 may be lowered at its latching edge until the pan structure may be 10 slid between the bottom forming element 4 and the lower edge of the cage structure 1 and the pan may be removed without materially disturbing or spilling the contents thereof, owing to the limited tilt required to remove the pan.

15 If preferred however, the latch may be released as soon as the flange 5 has cleared the same, so that the latch will return into the path of the extension 18, thus retaining the pan structure within the cage structure until the latch is moved 20 out of the path thereof, although the bottom 4 may swing to full open position, as indicated by dotted lines in Fig. 2.

With this form of device, the latch structure as well as the hinge structure will be entirely 25 concealed from casual view, thus enhancing the ornamental effect of the cage structure and by forming the hinge as shown, the bottom forming member may be easily attached to the body of the cage, or may be easily detached therefrom, 30 if desired.

It will likewise be seen that the ends 9 of the bracket 6, which extend at right angles to the face of the bracket, will prevent the bottom forming member 4 from casually disengaging from 35 the tongue 7, when the tongue is properly bent inwardly after being entered through the slot 8. In detaching the bottom forming member 4, from the cage structure 1, it is but necessary to bend outwardly the free end of the tongue 7 until it 40 will release from the slot.

The bottom of the pan structure 17 is pref-

erably depressed to form rounded shoulder 19, which will engage the edge of the bottom forming member 4, when the member 4 is released and starts to descend, thus preventing the pan from instantly sliding off the bottom the instant the bottom is first released from the latch 11.

If desired, a spring member 20 may be attached 80 to the band 2 with its free end curved and engaged with the bottom forming member 4 substantially at the point of connection of the flange 5 with the remainder of the bottom forming member, so that the swinging action will be more gradual and may be made of sufficient strength 85 to return the bottom member 4 to closed position as soon as the pan structure has been removed.

While the description and drawing illustrate in 90 a general way certain instrumentalities which may be employed in carrying the invention into effect, it is evident that many modifications may be made in the various details without departing 95 from the scope of the appended claims, it being understood that the invention is not restricted to the particular examples herein described.

What I claim is:

1. The combination with the body of a cage 100 structure, of a bottom forming member hinged thereto, a pan structure adapted to be entered in said cage structure, and a latch member adapted to retain either the bottom forming member or pan structure in closed relation with the cage 105 structure.

2. The combination with the body of a cage and a bottom forming member hinged thereto, 110 of a latch which serves to engage and support said bottom forming member in closed position, a hood structure serving to conceal and carry said latch into and out of engaging position, a spring means serving to swing said hood and latch into engaged position, and means to conceal 115 said spring from casual view.
